CREAMER

Russel Wright, New York, N. Y.

Application July 6, 1949, Serial No. 3,717

Term of patent 7 years

(Cl. D44—9)

To all whom it may concern:

Be it known that I, Russel Wright, a citizen of the United States of America and a resident of the city of New York, Borough of Manhattan, county of New York, and State of New York, have invented a new, original, and ornamental Design for Creamer, of which the following is a specification, reference being had to the accompanying drawing, forming a part hereof, in which—

Fig. 1 is a side elevational view of a Creamer, showing my new design.

Fig. 2 is a top plan view thereof.

Fig. 3 is an elevational view of the creamer taken from the right of Fig. 1.

I claim:

The ornamental design for a creamer, as shown.

RUSSEL WRIGHT.
